C. F. UNCKRICH
DOOR LOCK FOR OPEN END VAULTS,
APPLICATION FILED SEPT. 2, 1919.

1,375,645.

Patented Apr. 19, 1921.

UNITED STATES PATENT OFFICE.

CLARENCE F. UNCKRICH, OF GALION, OHIO.

DOOR-LOCK FOR OPEN-END VAULTS.

1,375,645.

Specification of Letters Patent. Patented Apr. 19, 1921.

Application filed September 2, 1919. Serial No. 321,110.

To all whom it may concern:

Be it known that I, CLARENCE F. UNCKRICH, a citizen of the United States, residing at Galion, in the county of Crawford and 5 State of Ohio, have invented certain new and useful Improvements in Door-Locks for Open-End Vaults, of which the following is a specification.

This invention relates broadly to burial 10 vaults, and has particular reference to the closure structure thereof. The object of the invention resides in the provision of a burial vault of the so-called open ended variety and in means of an improved nature for locking 15 the closure of the open end of said vault, said means serving to unite the closure in secured relationship with the body of said vault so that the interior of the latter will be substantially hermetically sealed and to 20 thus prevent extraneous fluids from gaining access to the interior of said vault after the latter has been finally sealed.

To this end, the invention provides a vault closure upon the inner face of which is 25 mounted a plurality of locking plates which are adapted to be projected into or out of locked engagement with a flange surrounding the open end of the vault, and in the provision of independently operable means 30 for effecting the projection and retraction of said locking plates into and out of locking engagement with said flange, said means being of such character as to independently and selectively project each of said locking 35 plates into engagement with said flange so that a tightly sealed relationship will exist between said closure and flange irrespective of structural imperfections in the formation of said flange, the arrangement being 40 such as to insure a very tight fit between the closure and flange along all points of the latter and to thus prevent air or other fluids from unduly entering the interior of the vault.

45 A further object of the invention resides in the provision of improved means for operating the locking plates, said means being in the nature of a plurality of cam members, one of which being allotted to 50 each of said locking plates and are capable of being independently actuated, said cam members embodying surfaces which will cause the locking plates to be projected into locking engagement with the vault flange 55 and are further formed with cam surfaces which act upon said plates to rock the latter

laterally of said closure, subsequent to the projection of the plates into locking positions and in this manner will serve to draw said closure into firmly seated relation with 60 respect to said flange.

A still further object of the invention resides in the provision of means for guiding the locking plates during their movements and to render the construction of the 65 closure positive and reliable.

With these and other objects in view, as will appear as the description proceeds, the invention accordingly consists in the novel features of construction, combination of elements and arrangement of parts, hereinafter to be fully described and to have the scope thereof pointed out in the appended claims.

In the accompanying drawing, forming 75 a part of this specification, and in which similar characters of reference denote like and corresponding parts:

Figure 1 is a transverse vertical sectional view taken through an open end grave vault, and disclosing the application of the locking mechanism comprising the present invention to the closure for said vault.

Fig. 2 is a horizontal sectional view taken along the line 2—2 of Fig. 1.

Fig. 3 is a front view of one of the cam 85 members, and,

Fig. 4 is an edge view thereof.

Referring more particularly to the details of the invention, use is made of a grave vault 1 wherein is provided an open end 2, 90 the latter being capable of being closed by means of a removable closure 3. In this instance, the grave vault 1 is provided with an angle iron or flange 4, which is preferably welded to the interior surfaces of said grave vault adjacent to the open end thereof and the flange 4 is of the configuration of said vault and is adapted to form a seat for the marginal edges of the closure. A gasket 5 is preferably provided between the meeting 100 faces of the flange 4 and the closure 3, said gasket serving as a seal for this joint and also acts to exclude moisture and air from the interior of the vault after the closure has been finally seated.

105 In order to draw the closure 3 into seating engagement with the flange 4 and to lock the same in this engagement, the inner surface of the closure is formed with a plurality of locking plates or members 6. The latter are of substantially skeleton formation, so as to be relatively light in weight

and yet to possess the desired rigidity and strength, and in this instance said plates are provided with key-hole slots 7 through which headed studs 8 are arranged to project. By this construction the narrowed shoulders of said studs will normally operate within the restricted portions of the slots 7, so that said plates will be securely held in slidable relationship with respect to said closure and yet are capable of being removed therefrom when said studs have their heads brought into registration with the enlarged portions of said slots. Obviously, when the fingers 9 of the plate 6 are brought into contact with the inner surfaces of the flange 4, said closure will be retained in locked relation with the vault. It will be observed that the plates 6 are of considerable width, and in effect are disposed for engagement with all parts of the flange 4 so that when projected into locking positions, said closure will be drawn toward said flange along every point of its margin thus tending to secure a wedged engagement between the closure and the flange. The necessity for the seal between the closure and the flange 4 is of utmost importance since if a small leak should exist in the joints formed thereby, the utility of the vault would be rendered void as air or moisture could readily seep through such a leak and the contents of the vault thus exposed to the danger of rapid deterioration. It will be apparent that as the description proceeds, it is the purpose of the present invention to provide a structure wherein a tight seal will exist and to thus overcome what is believed to be the defects in prior structures of an analogous nature.

In order to protect the plates, the latter are provided with reduced inner portions 10 which carry fixed pins 11. These pins are arranged to operate within cam shaped grooves 12 formed in a plurality of rotatable actuating members 13. The latter are arranged upon the inner surface of the closure 3 and are distributed so that each of said plates 6 will be provided with its individual actuating member, this being in contrast to prior structures wherein the locking plates are provided with a common actuating member. The members 13 are preferably formed with circular bearing projections 14, which are arranged to be received within bearing openings 15 formed in the closure 3, and the projections may be threaded to receive binding nuts 16 and serve to maintain said actuating members in their applied positions upon the inner surfaces of said closure. The other ends of the projections 14 may be provided with wrench receiving portions 17, by means of which said actuating members may be exteriorly rotated.

The members 13 have their grooves 12

so formed that the inner ends of the latter will be nearest to the axes of said actuating members and from these inner ends, the said grooves are gradually formed so as to be positioned nearer the peripheries of the actuating members, thus, said grooves provide eccentric plate projecting portions 18 and other portions 19 which are concentric to the axes of the actuating members. Further, the latter are formed with other cam surfaces 20 which are disposed on the inner faces thereof and extend inwardly of the vault, said surfaces 20 being located contiguous to the peripheries of the actuating members, however, it will be observed that the inclined surfaces 20 do not begin until the eccentric portions 18 of the grooves 12 terminate into concentric portions 19 of said grooves. Thus, said actuating members are so formed that when the same are initially rotated, the plates 6 are projected outwardly to prevent the withdrawal of the closure from the flange and after being thus projected, the inner ends of said plates will be brought into contact with the surfaces 20, so that said plates will be rocked transversely and in this manner their fingers 9 will be wedged into engagement with the flange 4 so that said plates will act as levers for drawing the closure 3 into firmly seated relation with the gasket 5 or in other words the flange 4. It will be observed that the fulcrum which is afforded by the studs 8 is so positioned that said actuating members will be afforded considerable leverage in rocking the plates transversely into engagement with said flange, thus tightly drawing the closure into a seated position upon the flange. The actuating members may be provided with removable cover plates 21 which define guide grooves in the actuating members for the reception of the reduced inner ends of the locking plates, thus serving to retain the pins 11 of said plates in seated relation with the grooves 12. Spring pressed pawls 22 are pivotally mounted upon the inner face of the closure and may be so rotated that the same will be forced, by means of springs 23, into engagement with ratchet teeth 24 provided upon the locking members. Thus, when the vault is finally sealed, the actuation of said members 13 will be prevented. When not in use, said pawls may be swung to assume inactive positions and retained therein by the springs 23.

By thus providing means for individually operating the locking plates, the present invention effects a structure whereby a tightly sealed relationship will exist between the closure and the vault body when the parts are in their finally assembled condition. It is common to vaults of this character that imperfections will exist in the shape and positions of the flange 4, hence, if one portion 130

thereof should be inset farther than the remaining portions, the present invention will provide means whereby this imperfection will be overcome, since the operation of each 5 locking plate is rendered local and the desired pressure may be imparted to any single part of the closure, to draw the latter into seating engagement with the flange. Prior structures mainly disclosed devices 10 which are operated from a common device, hence it will be manifest in the earlier forms of device that an inset imperfection in the flange thereof would result in the application of pressure by the locking fingers upon 15 the inset portion to a greater extent than upon the remaining portions, and the loss of pressure upon the remaining portions has frequently resulted in air or other fluid leaks. This is believed to be overcome by 20 the present invention, wherein the selectively actuated locking plates may impart the desired necessary pressure to any part of the closure margin, thus sealing the vault around all edges of its open end and rendering 25 the same practical for effective service.

I claim:

1. In a metallic grave vault, a closure for the entrance of said vault, a flange rigidly carried by said vault contiguous to its entrance and against which said closure is arranged to seat, means for locking said closure in secured relationship with said seat, comprising a plurality of locking plates

slidably mounted upon the inner face of said closure and capable of being projected 35 into and out of engagement with said flange, circular cam members independently mounted for rotation upon the inner face of said closure, said cam members being provided with grooves disposed eccentrically to the 40 axes of rotation thereof and with continuing grooves disposed concentrically to the axes of rotation, projections provided upon the inner ends of said plates and arranged to be received within said grooves, whereby 45 upon the selective rotation of said cam members said plates may be projected into engagement with said flange, and inwardly projecting cam surfaces provided upon the inner vertical faces of said cam members 50 contiguous to the concentrically arranged grooves, whereby after said plates have been projected into engagement with said flange by the eccentric grooves of said cam members, the inwardly projecting cam surfaces of said members will engage with said plates to rock the latter laterally into firm 55 frictional engagement with said flange.

2. The structure as specified in claim 1, and wherein the cam members are provided 60 with ratchet teeth capable of engaging with spring pressed pawls to prevent undue retraction of said plates from their locking positions.

In testimony whereof I affix my signature. 65
CLARENCE F. UNCKRICH.
